UNITED STATES PATENT OFFICE.

LOUIS PHILIPP EY, OF DIMBOOLA, VICTORIA, AUSTRALIA, ASSIGNOR TO
ERNST RUDOLPH EY, OF DIMBOOLA, VICTORIA, AUSTRALIA.

HORSE-COLLAR.

No. 834,794.

Specification of Letters Patent.

Patented Oct. 30, 1906.

Application filed November 4, 1905. Serial No. 285,894.

To all whom it may concern:

Be it known that I, LOUIS PHILIPP EY, a subject of the King of Great Britain and Ireland, residing at Dimboola, in the State of Victoria, Commonwealth of Australia, have invented certain new and useful Improvements in Horse-Collars; and I do hereby declare the following to be a full, clear, and exact description of the invention, such as will enable others skilled in the art to which it appertains to make and use the same.

This invention relates to improvements in collars for horses; and its object is to provide a construction, dispensing with the need for separate hames, which shall be strong and durable and shall allow of adjustment of the hame-hooks in the most suitable working positions and also of easy repair.

My construction is adapted to promote the keeping of the collar in correct shape and to allow it to be put on the horse and taken off easily.

The collar has a top which opens and has a base which is hinged, the hinge, of any suitable kind, being at the lower ends of a metal fore-wale which forms the collar-frame and is, except at its top and bottom extremities, tubular. To this frame is connected the padded or other collar-body of any suitable construction, and a leather or any other desired covering is provided on the frame. At the collar-top are means to prevent distortion. Thus the frame has a tongued and grooved joint or the like, and there is also ordinarily a hinged fall.

The tongued and grooved joint which I have shown is particularly necessary because of the use of the tubular fore-wale, which in turn is a necessary part of the pivoted hame-hook construction which I will describe later.

Two rounded surfaces would not fit properly one upon the other, and it is to this end that I make one of the tubular fore-wales grooved and the other with a tongue, as shown in Fig. 2, and provide the hinged fall adapted to bind the two together when it is closed; but the main feature of the invention is the provision upon the tubular frame at each side of a loose sleeve or the like adapted to swing and an adjustable connecting-plate intermediate between the said sleeve and the hame-hook and so arranged as to allow of any hook being located higher or lower, as desired, relatively to the said plate or sleeve. These features

may, as hereinafter pointed out, be modified, 55 while preserving the essentials.

In the drawings herewith the invention is illustrated.

Figure 1 shows the collar in front view in fully-opened position. Fig. 2 shows in plan 60 view the collar-top closed. Fig. 3 shows the connecting-plate in front view, and Fig. 4 represents in horizontal sectional view a tubular metal fore-wale with swinging sleeve and hame-hook-connecting plate. 65

In the views, *a b* are two tubular or mainly-tubular metal fore-wales or members having respective tops *c d*, which when closed form a tongued and grooved or equivalent joint and are further united by a fall-ring *e*, hinged as 70 at *f*.

g indicates any suitable collar-body, and *h* any suitable padding or inner surface. *i* shows a lower hinge adapted to open to a predetermined maximum extent, which may be 75 as illustrated in Fig. 1. This hinge will in ordinary practice be covered with leather.

j k at each side are projections, ribs, or rings on or around the members *a b*, and between these on each side of the collar is a 80 loose or movable sleeve *l*, having one or more suitable lugs *m*, which may be curved. An upper and a lower lug are shown, the space between receiving the butt of a hame-hook-connection plate *n*, having a series of slots or 85 sockets *o*. There may be any socket, joint, or fastening whereby the plate *n* may be secured, removably or otherwise, to sleeve *l*, rivets *p*, as shown, or nuts and screws being usually provided. Details as to the connection of hame-hook *p* to plate *n* may vary, what I show being bolt *r* with nut, the bolt passing through lugs *s* on the hook and perforations *t* in plate *n*. By slitting plate *n* and twisting the slotted lugs *u* thus formed 90 the recesses or sockets *o* may be produced.

When the parts are assembled and secured as in Fig 1, not only is there pivotal movement upon bolt *r*, but also upon fore-wales *a* and *b*. The advantages of the latter feature 100 are, first, that the movability of the sleeve allows of easy sewing up and repair of the leather casing and the padding of the collar at any time; secondly, that the leverage 105 upon the fore-wales of attachments firmly fixed to the fore-wales for hame-hook connection would in working be considerable, especially by draft-horses, and as this leverage

would tend to wrench the fore-wales and damage them I avoid it by employing loose sleeves *l*. In some cases, however, the shanks of hooks *q* are connected to the lugs *5* or equivalents of the sleeves without having intermediate plates *n*.

It will be noted in connection with the special features of advantage above pointed out that the strain upon the hame-hooks *q* *10* does not come upon any one portion of the collar nor entirely upon the fore-wales, but that a rearward draft upon the hame-hooks presses the lugs or plates *m* against the face of the padding *g*. These lugs being in the *15* form of plates the strain is more evenly distributed over the entire face of the collar and against the horse's neck than if the hame-hooks were attached by means at the outer edge of the collar or were unsupported by the *20* padding *g*. If the plates *m* were not capable of bending back to a place against the face of the padding *g*, then the rearward strain would tend to bend the plates or lugs *m* and to bend the fore-wales. If the hame-hooks *25* *25* swung rearwardly directly back from the collar without the intermediate plate *m*, so pivoted as to rest against the collar, then the collar would be distorted in a very short time.

Terret-rings and any other desired parts *30* for harness connections may be secured to the tubular wales *a b* or to other suitable portion or portions of the collar.

In Fig. 1 the hame-hooks are (to illustrate the adjustability thereof) shown placed at *35* different heights. When nuts and screws or the like are used at *p*, the plates *n* may also be adjusted in relative height at will. The number of lugs *u* or of other members provided to promote adjustability of height in *40* assembling the parts is not limited to what is illustrated.

What I claim as my invention, and desire to secure by Letters Patent of the United States, is—

45 1. A horse-collar having fore-wales of tubular metal on each side thereof and hinged at

the lower ends, plates each having a bent portion encircling one of said fore-wales to form a pivotal connection therewith for movement in a horizontal plane, and hame- *50* hooks having pivotal attachment to said plates.

2. A horse-collar having fore-wales of tubular metal on each side thereof and hinged at the lower ends, plates each having a bent portion encircling one of said fore-wales to form a pivotal connection therewith for movement in a horizontal plane, said plates being provided with a series of vertically-disposed *55* sockets, hame-hooks adapted to be adjusted in said sockets, and means for pivoting said hooks in said sockets.

3. A horse-collar having tubular metal fore-wales on each side thereof, a sleeve encircling each of said fore-wales and having *60* projecting lugs, plates held to said lugs having outwardly-projecting tongues forming a series of vertically-disposed sockets, hame- *65* hooks engaging with one or more of said sockets and pivoted therein, and a removable pintle passing through said sockets and hame-hooks. *70*

4. A horse-collar having tubular metal fore-wales on each side thereof, separated ribs on each fore-wale, a sleeve encircling *75* the said fore-wales and located between the said ribs, having two oppositely-placed projecting lugs formed in one piece therewith, a plate held between the two lugs and riveted thereto having outwardly-projecting *80* tongues forming a series of vertically-disposed sockets, a hame-hook having at the base thereof one or more tongues for engaging within the sockets on the said plates, and a removable pintle passing through said sockets and hame-hooks. *85*

In witness whereof I have hereunto set my hand in the presence of two witnesses.

LOUIS PHILIPP EY.
